**CONTROL DESK FOR CLASSROOM
INSTRUCTION**

Judson E. Cornish, 3211 Tallywood Drive, Apt. 1,
Fayetteville, N.C. 28303

Filed Oct. 28, 1968, Ser. No. 14,193

Term of patent 14 years

Int. Cl. D6—01

U.S. Cl. D33—7

FIG. 1

FIG. 2

FIG. 3

FIG. 4

FIG. 5

FIG. 6

FIG. 1 is a perspective view of a control desk for classroom instruction, showing my design;

FIG. 2 is a top plan;

FIG. 3 is a rear elevation;

FIG. 4 is a front elevation;

FIG. 5 is a side elevation, taken from the right side, the elevation from the left side being a mirror image thereof; and

FIG. 6 is a bottom plan.

I claim:

The ornamental design for a control desk for classroom instruction, as shown and described.
